UNITED STATES PATENT OFFICE.

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

AUTOMATIC TRAIN-CONTROL SYSTEM.

1,308,543.

Specification of Letters Patent.

Patented July 1, 1919.

Application filed May 1, 1916. Serial No. 94,687.

To all whom it may concern:

Be it known that I, WINTHROP K. Howe, a citizen of the United States, and a resident of the city of Rochester, in the county of Monroe and State of New York, have invented a new and useful Improvement in Automatic Train-Control Systems, of which the following is a specification.

This invention relates to automatic train control systems, and more particularly to the means used for communicating the impulses or influences necessary for the operation of the system to a moving vehicle at points along the track over which the vehicle is traveling. More specifically, the invention relates to such means of communication which includes a contact shoe carried by the vehicle and arranged to coöperate mechanically and electrically with suitable contact rails or ramps located at intervals along the track over which the vehicle travels.

One of the objects of this invention is to devise a simple and efficient contact shoe for automatic train control systems which will open or close certain electric circuits positively and reliably as the vehicle travels over the track, and which may also be used to control electric circuits selectively according to the direction in which the vehicle is traveling.

A further object of the invention is to devise an arrangement and construction of parts whereby frost, sleet, ice and the like on the ramp will not interfere with the electrical contact between the contact shoe and a ramp.

A further object of the invention is to devise a simple means for economically oiling the movable parts of a contact shoe and the contact surface of the several ramps with which this contact shoe engages.

A still further object of the invention is an arrangement and construction of parts whereby the contact surface of the several ramps and the important moving parts of the contact shoe, which are subjected to the greatest wear, may be supplied with oil, thereby enabling a greater contact pressure between the shoe and the ramps to be used without objectionable wear than could otherwise be used, thus improving the electrical contact of the shoe with the ramps.

Other objects and advantages will appear as the description of the invention progresses, and the novel features of the inven-

tion will be particularly pointed out in the appended claims.

The invention consists in the parts, and in the arrangements and combinations of parts, which are more fully set forth hereinafter. 60

In describing the invention in detail, reference is had to the accompanying drawing, in which is illustrated a preferred physical embodiment of the invention, in which like reference characters designate like parts in 65 the several views, and in which:

Figure 1 is a vertical sectional view of a contact shoe embodying the invention, the line on which the section is taken being indicated by the line 1—1 in Fig. 2; 70

Fig. 2 is another vertical section through the contact shoe, said section being taken at right angles to the section shown in Fig. 1 and substantially on the line 2—2 in Fig. 1, and 75

Fig. 3 shows a portion of the contact shoe and a type of ramp which is preferred for use with the form of contact shoe illustrated.

Referring to the accompanying drawing, the contact shoe is designed to be supported 80 in any suitable way (not shown), preferably adjustably on some part of the vehicle, as on a journal box, an axle, a truck side frame or the like; and since one function of the contact shoe is to establish electrical communication between the several ramps with which it engages and suitable controlling devices on the vehicle, the contact shoe is preferably mounted on a bar 5 of wood or other suitable insulating material, so that the shoe 85 as a whole is insulated from the frame or body of the vehicle. The contact shoe, as a whole, comprises a body portion or casting A which in effect consists of two chambers or casings B and C arranged one above the other, the upper casing C being provided

with a suitable removable cover D, and the front of the lower casing B being provided with a removable cover plate E. The body portion or casting A of the whole contact shoe is fastened to the supporting bar or shoe beam 5 by two bolts 6, a plate or washer 7 being interposed between the nuts of said bolts and the bar 5. The portion of the shoe which actually contacts with the several 95 ramps consists of a disk or foot 8 having an integral bearing stud 9 which is revolubly mounted in a block 10, said bearing stud 9 being held in said block 10 by two pins 11 105 engaging a circumferential groove in said 110

bearing stud. The under face of the foot 8 is formed with a circular recess in which a pad 12 of felt or similar material is fastened by screws and washers 13. A number 5 of bores or channels 14, the purpose of which is explained hereinafter, extend from the upper face of the foot 8 to the recess in its under face. The block 10, carrying the foot 8 of the shoe, is supported by two parallel 10 crank arms, each of which is pivotally supported at its upper end to the body portion or casting A of the contact shoe and at its lower end to the block 10; and since the construction of these crank arms and their 15 associated parts are the same in most respects, the general description of one will suffice for both, and for convenience the corresponding parts will be designated by the same reference characters with the distinctive exponent 1 added thereto.

Each of the crank arms 15 has a laterally projecting bearing stud 16 (see Fig. 2) at its lower end which extends through a corresponding bore near one end of the block 20 10, a washer 18 and a cotter pin 17 passed through said stud 16 serving to hold the block 10 in place on said bearing stud. Extending longitudinally of the bearing stud 16 for part of its length is a comparatively 25 small hole or bore 19, the outer exposed end of which is closed by a suitable plug 20; and communicating with the bore 19 is another 30 channel or passage 21 which extends transversely of the bearing stud 16 to its outer surface; and when the contact shoe is not in 35 engagement with a ramp and the parts thereof are in the normal position shown in the drawing, the channel 21 is in communication with a channel 22 extending through 40 the block 10 to the outer surface of the bearing stud 9, as shown to the best advantage in Fig. 1. Extending longitudinally of each 45 crank arm 15 is a channel or passage 23, the upper end of which is closed by a suitable 50 plug 24 and the lower end of which communicates with the passage 19, as shown in Fig. 2. Integral with the upper end of each 55 crank arm is an upper bearing stud 30 which extends through the front and rear walls of the lower casing B of the body portion A 60 of the contact shoe and which is held in place by a collar 31 fastened thereto by a pin 32. Extending longitudinally for part of the length of the upper bearing stud 30 65 from its front end is a bore or channel 25, the outer end of which is closed by a plug 26, and the inner end of which communicates with another channel 27 extending to the outer surface of the corresponding bearing stud. In the body portion or casting A 70 of the contact shoe immediately above the outer end of each crank arm 15 is a downwardly extending channel 28, the lower end of which is in communication with the channel 27 in the corresponding crank arm when

the parts of the shoe are in their normal position, and the upper end of which communicates with a pipe 29 leading to a suitable oil pump hereinafter described.

The upper bearing stud 30 of each of the 70 crank arms 15 is encircled by a torsion spring 33, one end of which is bent and fixed to the rear wall of the lower casing B of the contact shoe, as indicated by the numeral 34, and the other end of said spring is secured to the corresponding bearing stud 30, this connection being made between a bent end 35 of the spring 33 and a collar 36 which is fixed to the corresponding bearing stud 30 by a key 37. In the case of the crank arm 15, 75 which is the lefthand crank arm as the shoe is viewed in Fig. 1, the collar 36 has integral therewith a cam 38, shown to the best advantage in Fig. 1. Above the cam 38 is an arm 40 journaled on a pin 41 secured to a lug 42 fixed to or integral with the side wall of the lower casing B; and mounted on a pin 43 in this arm 40 is a roller 44 arranged to press against the edge of the cam 38. A rod 45 is pivotally connected by a pin 46 to the outer or free end of the arm 40, and this rod 45 extends upwardly through a slot 47 in the bottom of the upper casing C. Upon the rod 45 are disposed spring caps 48 and 49, the spring cap 48 bearing against 80 the arm 40, and the spring cap 49 bearing against the inclined face of a projection 50 integral with the bottom of the upper casing C; and encircling the rod 45 and interposed between the caps 48 and 49 is a compression coil spring 51, which serves to press the arm 40 downward. In the upper casing C is a squared shaft 53 which is journaled at 85 its ends in suitable bearing supports 52 bolted to the end walls of said casing, and fastened on the squared shaft 53 is a crank 90 arm 54, the outer end of which is pivotally connected to the upper end of the rod 45.

As indicated hereinbefore, one function 95 of the contact shoe is to open and close certain controlling circuits, and to perform this function a number of contact springs are supported in the upper casing C in position to be engaged by contact sectors secured to the shaft 53. For the sake of simplicity one 100 set of these contact fingers has been illustrated and are shown as fastened to a block 55 of suitable insulating material fixed in the upper casing C. The contact springs 56 are arranged side by side and are fastened to 105 said insulating block 55 by bolts which also serve as binding posts. In the form illustrated each contact spring extends downwardly along one face of the block 55, is doubled back upon itself, and then extends 110 upwardly and terminates in a V-shaped contact piece; and to limit the movement of the contact piece outward from the block 55 a stop 57 is secured to the block 55, as clearly 115 shown in Fig. 1. The part arranged to co- 120

operate with the two contact springs 56 is shown as a sector-shaped member 58 of suitable insulating material fitted snugly on the squared shaft 53; and secured in any suitable way to the curved face of the member 58 is a metallic plate 59 which is of sufficient width to touch both of the contact springs 56.

The oil pump, hereinbefore referred to, comprises a body portion or casing P, the lower end of which bears upon the front cross rib of the lower casing B, as shown to the best advantage in Fig. 2, said pump casing P being secured by a tap bolt 61 to the main casting A of the contact shoe, as shown in Fig. 1. In the lower end of the pump casing P is a longitudinal bore 62, the upper end of which communicates with a smaller bore 66 and is shaped to form a seat for the ball check 63, said ball check being held against its seat by a light compression spring 64 bearing at its lower end against a plug 65 secured in the lower end of the bore 62. The bore or chamber 66 constitutes the cylinder or pump chamber of the pump proper and communicates at its upper end with an enlarged longitudinal bore 67, and extending through the bore 67 and part way into the pump chamber 66 is a pump plunger 68 which extends upwardly through the bottom of the upper casing C. The pump plunger 68 has integral therewith a collar 69 fitting in the bore 67 and held against upward movement by pins 71; a compression coil spring 70 being disposed between the collar 69 and the bottom of the bore 67. Integral with the bottom of the upper casing C are two upwardly extending lugs 72 in which is fastened a horizontal pin 73, and journaled on said pin 73 is an angle lever L. This angle lever L is disposed substantially in the plane of the pump plunger 68, and the horizontally extending arm 74 of said angle lever has an adjustable bolt 75 extending therethrough into position to strike the upper end of the pump plunger 68 when said arm 74 is moved downward, said bolt 75 being provided with a jam nut 76. The vertically extending arm 77 of the angle lever L has journaled in its outer end a roller 78 which is arranged to bear against a cam 79 fixed to the shaft 53, as clearly shown in Fig. 1.

The pump chamber 66 communicates by a passage 80 with a check valve chamber 82, the outer end of the passage 80 being closed by a suitable plug 81, and the upper end of the chamber 82 being closed by a plug 83¹. The lower end of the chamber 82 communicates with a passage 84 and is formed to provide a seat for the ball check 83; and the passage 84 leads to a pipe 85 threaded at one end in the body portion P of the pump, and this pipe 85 extends through a side wall of the lower casing B and is held in place by a nut 86. An oil tank or reservoir 87 is fas-

tened to the side walls of the casings C and B by tap bolts 88, and in the upper end of the tank 87 is a filling opening 89 covered with a suitable cap 90, a strainer 91 for the oil being preferably supported under the opening 89. In the bottom of the oil tank 87 is a depression 92, in one wall of which a short length of pipe 93 is threaded; and the pipe 85 is connected to the pipe 93 by means of a short length of pipe 94 and two unions 95.

Referring to Fig. 3, the ramp R which is preferably used in connection with the contact shoe shown and hereinbefore described comprises an angle iron 96 having a comparatively narrow edge. This angle iron 96 may be supported in any suitable way, but is shown as having its horizontal leg fastened by a lag screw 97 to a support 98 of wood or other suitable material, there being comparatively thin washers or shims 99 interposed between the upper face of the support 98 and the horizontal leg of the angle iron 96, whereby a vertical adjustment of the angle iron 96 may be obtained by increasing or decreasing the number of these shims 99. As shown in Fig. 3, the angle iron 96, constituting the ramp R, is preferably positioned so as to engage the foot 8 of the contact shoe in line with its axis; but since there is always more or less of a side sway to the car, the axis of the foot 8 will be practically all of the time on one side or the other of the vertical leg of the angle iron 96, so that said foot 8 will be turned with a scraping action, which tends to clean the upper edge of the angle iron and scrape it clear of snow, sleet and ice.

Operation.

105

The parts of the contact shoe are shown in the drawing in the position which they assume when the shoe is not in engagement with a ramp. During the movement of the vehicle to which the shoe is attached, the shoe moves in a direction in the plane of the paper as viewed in Fig. 1, and at right angles to the paper as viewed in Fig. 2. The vehicle to which the shoe is attached may travel in either direction over the track, that is, the vehicle may be traveling in the normal direction of traffic or in the opposite direction. Assuming that the vehicle is traveling in the direction corresponding to that indicated by the arrow X in Fig. 1, when the foot 8 of the shoe engages the sloping end of a ramp this foot is forced to the left and upward, the crank arms 15 and 15¹ being correspondingly rocked to the left. By reason of the parallel arrangement of the crank arms 15 and 15¹ the foot 8 of the shoe remains parallel with the edge of the ramp during this swinging movement. When the crank arm 15 is swung to the left, the cam 38 is moved to the right; and it can

110

115

120

125

130

be readily seen from the shape of this cam shown in Fig. 1 that after a small angular movement of said cam, the roller 44 and the arm 40, to which said roller is attached, may move downward under pressure of the spring 51, thereby pulling down on the rod 45 which rocks the shaft 53 counterclockwise through a small angle. It can also be seen that further movement of the cam 38 after 10 this small angular movement does not move the roller 44, the arm 40 and the rod 45. The rocking movement of the shaft 53 may be used to either open or close certain circuits; but in the arrangement illustrated the 15 circuit which is normally closed by the contact of the contact plate 59 with the contact springs 56 is not disturbed by this movement of the shoe. In case the vehicle were traveling in the other direction, however, the 20 crank arms 15 and 15¹ would be swung to the right as viewed in Fig. 1, thereby moving the cam 38 to the left; and it can be readily seen from the shape of the cam 38 that the roller 44 and the arm 40 would be 25 forced upward against the opposition of the spring 51, thereby causing a clockwise movement of the shaft 53 through a small angle, which moves the contact plate 59 out of contact with the contact springs 56 to break 30 the circuit controlled thereby. During the movement of the crank arms 15 and 15¹ in either direction the torsion springs 33 are distorted, so that after the foot 8 of the shoe leaves engagement with the ramp these 35 springs serve to return the crank arms to their normal position as shown.

The operation of the oiling system is as follows: Oil in the reservoir tank 87 passes by gravity aided by the suction of the pump 40 through the pipes 93, 94 and 85 to the passage 84, thence past the ball check 83 into the chamber 82, and through the passage 80 into the pump chamber 66. When the shoe engages a ramp, the shaft 53 is 45 rocked in one direction or the other as explained hereinbefore and the cam 79 secured to said shaft bears against the roller 78 and pushes the vertical arm of the angle lever L to the right, as viewed in Fig. 1, regardless 50 of the direction in which the shaft 53 is turned; and after a certain amount of idle movement, which is determined by the adjustment of the bolt 75, the bolt 75 in the arm 74 of the angle lever L strikes the pump 55 plunger 68. In this way the pump plunger 68 is forced downward against the opposition of the spring 70 each time the shoe engages a ramp; and at each stroke of the pump plunger 68 downward, some of the oil 60 contained in the pump chamber 66 is forced past the ball check 63 into the chamber 64 through the pipes 29 and 29¹. As soon as the shoe leaves engagement with a ramp and the crank arms 15 and 15¹ return to their 65 normal position, the oil will flow through

the pipes 29 and 29¹ downward through the crank arms to the felt pad 12 in the foot 8 of the shoe, the route of the oil in the case of each of these crank arms being similar, said route in the case of the crank arm 15¹ being 70 along passage 28¹ (see Fig. 2) passages 27¹, 25¹, 23¹, 19¹ and 21¹ to the surface of the bearing stud 9 to the upper face of the foot 8 and thence by the passages 14 to the pad 12. It can be seen that the bearings of the 75 principal moving parts of the shoe are freely oiled and that the felt pad 12 is kept saturated with oil. The oil in the felt pad 12 is distributed over the upper edge of the ramp in a thin film, and not only serves to 80 decrease the friction between this upper edge of the ramp and the foot of the shoe but also apparently prevents frost and sleet from adhering so tightly to the ramp that it can not be easily scraped away by a moderate pressure between the shoe and said ramp. In other words, the oiling system serves the 85 dual function of minimizing the wear and in improving the electrical contact between that shoe and a ramp. By adjusting the stroke of the pump plunger 68 the rapidity with which the oil is fed to the bearings of the shoe and the felt pad 12 may be regulated with nicety so that, while there is no waste of oil, there is always sufficient oil to 90 accomplish the desired results. In this connection it should be noted that the pump is operated only when the contact shoe engages a ramp; and in this way the flow of oil is automatically regulated according to 95 the demand.

In all structures involving a ramp and a shoe for contacting with said ramp, it is not only highly desirable but my experience has shown that it is practically necessary 105 for best operation to oil the contact surface of the ramp; and when, as in the specific embodiment of my invention shown and hereinbefore described, in addition to oiling the contact surface of the ramp, a ramp having a comparatively narrow edge and a contact shoe having a revolute foot is used, the 110 most efficient combination is obtained.

Although I have particularly described the construction of one physical embodiment 115 of my invention, and explained the operation and principle thereof; nevertheless, I desire to have it understood that the form selected is merely illustrative, but does not exhaust the possible physical embodiments 120 of the idea of means underlying my invention.

What I claim as new and desire to secure by Letters Patent of the United States, is:

1. Means for communicating between a 125 moving vehicle and a fixed point comprising, in combination: a movable contact shoe carried by the vehicle; a ramp arranged to be engaged by said contact shoe; and means operated automatically by the movement of 130

said shoe upon engagement with a ramp for delivering a predetermined quantity of oil to the contact surface of the shoe, thereby causing a coating of oil to be distributed 5 over the contact surface of the ramp.

2. Means for communicating between a moving vehicle and a fixed point comprising, in combination: a contact shoe carried by the vehicle; a ramp having a relatively narrow contact edge and arranged to be engaged by said shoe; and means for automatically applying oil to the contact edge of said ramp. 10

3. Means for communicating between a moving vehicle and a fixed point comprising, in combination: a ramp; a contact shoe carried by the vehicle and having a rotatable part adapted to engage said ramp and to be automatically rotated by such engagement; 15 means for pressing the rotatable part of said shoe against said ramp; and means for automatically applying oil to the contact surface of said ramp as said shoe engages it. 20

4. Means for communicating between a moving vehicle and a fixed point comprising, in combination: a ramp having a relatively narrow contact edge; a contact shoe carried by the vehicle and having a rotatable part adapted to engage said ramp and to be automatically rotated by such engagement; 25 means for pressing the rotatable part of said shoe against the contact edge of said ramp; and means for automatically applying oil to the contact edge of said ramp as said shoe engages it. 30

5. Means for communicating between a moving vehicle and a fixed point comprising, in combination: a shoe carried by the vehicle and supported thereby to move relatively thereto; a ramp arranged to be engaged by said shoe; a compact pad of material capable of absorbing oil and secured to said shoe in position to touch the contact surface of said ramp; an oil tank carried by the vehicle; and means automatically operated by 40 said shoe for feeding oil to said pad as the shoe successively engages said ramps. 45

6. Means for communicating between a trackway and a moving vehicle comprising, in combination: a contact shoe carried by the vehicle; ramps located at intervals along the trackway in position to be engaged by said shoe; and means including a force pump operated when said shoe engages a 50 ramp for automatically supplying a predetermined quantity of oil to the contact surface of said ramp. 55

7. Means for communicating between a trackway and a moving vehicle comprising, in combination: a contact shoe carried by the vehicle; ramps located at intervals along the trackway in position to be engaged by said shoe; an oil reservoir on the vehicle, and means operated automatically by the 60 engagement of the shoe with each ramp for 65

feeding a predetermined quantity of oil from the reservoir to the contact surface of the shoe, thereby causing a coating of oil to be distributed over the contact surface of the ramp, said means being adjustable to vary 70 the quantity of oil supplied at each ramp.

8. Means for communicating between a trackway and a moving vehicle comprising, in combination: a contact shoe carried by the vehicle and having movable parts; ramps located along the trackway in position to be engaged by said shoe; a container for oil; said shoe being provided with passages constituting a path for the flow of oil from said container to the bearings of the 80 movable parts of said shoe and to the contacting surface thereof; and means for automatically forcing a fixed quantity of oil through said passages, whereby a coating of oil is applied to the contact surfaces of said 85 ramps and the bearings are lubricated.

9. A contact shoe for communicating between a trackway and a moving vehicle comprising, a conducting member revolvably supported by said shoe and carrying a pad of 90 material capable of absorbing oil; a container for oil carried by the vehicle; and means for causing a predetermined supply of oil to be supplied from the container to 95 said pad.

10. A contact shoe for communicating between a trackway and a moving vehicle comprising, a body portion having an enclosed casing; a circuit controlling device including a movable element having a normally closed position and two other circuit controlling positions; parallel crank arms pivotably connected to said casing at their upper ends; a foot pivotally connecting said crank arms at their lower ends; a cam operated by the swinging of said crank arms; and means controlled by said cam for operating said circuit controlling device from its normal position to either of its circuit controlling positions in accordance with the 100 direction of movement of said crank arms. 105

11. Means for communicating between a trackway and a moving vehicle comprising, in combination: a contact shoe carried by the vehicle; ramps having relatively narrow contact surfaces and located at intervals along the trackway in position to be engaged by said shoe; and means for automatically applying a substantially uniform coating of oil over the contact surfaces of 110 said ramps as said shoe successively engages them. 115

12. Means for communicating between a trackway and a moving vehicle comprising, in combination: a contact shoe carried by the vehicle; ramps having relatively narrow contact surfaces and located at intervals along the trackway in position to be engaged by said shoe; said shoe comprising a rotary 125 part adapted to engage said ramps and to be 130

rotated by such engagement; a pad of material capable of absorbing oil carried by said rotary part; means for pressing the rotary part of said shoe against said ramps; and 5 means for supplying a fixed quantity of oil to said pad each time said shoe engages a ramp.

13. Means for communicating between a trackway and a moving vehicle comprising, 10 in combination: a contact shoe carried by the vehicle; ramps having relatively narrow contact surfaces and located at intervals along the trackway in position to be engaged by said shoe; said shoe comprising a rotatable part adapted to engage said ramps and to be automatically rotated by said engagement to scrape the contacting surface of said ramps; and means for automatically applying a fixed quantity of oil to the contacting surfaces of said ramps each time said shoe engages a ramp.

14. A contact shoe for communicating between a trackway and a moving vehicle comprising, a movable part supported by said 25 shoe and carrying a pad of material capable of absorbing oil; an oil container carried by the vehicle; a passage constituting a measuring chamber adapted to hold a predetermined amount of oil, said chamber being 30 connected with said oil container; passages constituting paths for the flow of oil from said measuring chamber to said pad, and means operated by said movable member for cutting off the connection between said oil 35 container and said chamber and for forcing the oil in said chamber through said paths to said pad.

15. A contact shoe for communicating between a trackway and a moving vehicle comprising, in combination: a movable contact 40 shoe carried by the vehicle and provided with a compact pad of absorbent material arranged to rub over the contact surface of a ramp engaged by said shoe; an oil reservoir carried by the vehicle; and means operated automatically by the movement of the

shoe upon its engagement with a ramp for regulating the supply of oil from the reservoir to said pad to maintain the pad substantially saturated.

50

16. A contact shoe for communicating between a trackway and a moving vehicle comprising, in combination: a contact shoe carried by the vehicle and having movable parts; an oil container carried by the vehicle; passages constituting paths for the flow of oil from said container to the bearings of said movable parts; and means operated by said movable parts for forcing a predetermined quantity of oil through said paths as said shoe is successively operated.

55

17. A contact shoe for automatic train control systems comprising a movable element adapted to be displaced by engagement with ramps in opposite directions according to the direction of movement of the vehicle over the track, a circuit controller including a movable part and adapted to open upon movement of said part from its normal position in one direction but to remain closed 65 upon like movement in the opposite direction, and means operatively connecting said movable element of the shoe with said movable part of the circuit controller, whereby the circuit controller will be opened when the vehicle passes a ramp traveling in one direction but will remain closed when the vehicle travels by that ramp in the opposite direction.

70

18. A contact shoe for automatic train control systems comprising a body portion, crank arms pivotally connected at one end to the body portion, a contacting foot pivotally connected to the other ends of the crank arms, separate torsion springs operatively 75 connected to the crank arms and tending to hold them in a predetermined normal position, and circuit controlling means operated by the movement of the crank arms from their normal position in one direction.
